UNITED STATES PATENT OFFICE.

MICHAEL E. REILLY, OF MONTESANO, WASHINGTON.

RAZOR-STROP.

SPECIFICATION forming part of Letters Patent No. 452,112, dated May 12, 1891.

Application filed December 16, 1890. Serial No. 374,892. (No model.)

To all whom it may concern:

Be it known that I, MICHAEL E. REILLY, a citizen of the United States, residing at Montesano, in the county of Chehalis and State 5 of Washington, have invented a new and useful Razor-Strop, of which the following is a specification.

The invention relates to improvements in razor-strops.

10 The object of the present invention is to simplify and improve the construction of razor-strops and provide a device adapted to be quickly arranged to present a strap, canvas, or hone-faces to a razor.

15 The invention consists in the construction and novel combination and arrangement of parts hereinafter fully described, illustrated in the accompanying drawings, and pointed out in the claims hereto appended.

20 In the drawings, Figure 1 is a perspective view of a razor-strop constructed in accordance with this invention, the lever being raised. Fig. 2 is a similar view, the lever being closed to tighten the strap. Fig. 3 is a 25 longitudinal sectional view. Fig 4 is a detail perspective view of the lever, illustrating the manner of securing the strap. Fig. 5 is a detail view illustrating the strop constructed of one continuous piece.

30 Referring to the accompanying drawings, 1 designates the body of a razor-strop, having one end 2 formed into a handle portion and provided between the handle portion 2 and the other end with hone-faces 3, which are 35 adapted to be exposed for use by removing a strap 4 from a stationary roll or cylindrical bar 5, arranged at the end 6 of the body and provided with a recess 7 to receive the end 6. The strap 4 has one end 8 secured to a lever

40 9, and it may be one continuous piece of material, such as leather, and pass around the roll or cylindrical bar 5 and be secured to the body 1; but it is preferable to construct the strop as illustrated in Fig. 3 of the accompanying drawings and connect the strap 4 with a strip 10 of canvas or other suitable material 45 desirable for use in a razor-strop.

The ends 8 and 11 of the strap 4 and strip 10 are arranged in curved grooves 12 and 13 50 in the outer faces of the lever 9 and the handle portion 2 of the body, and the said ends 8 and 11 are secured in the grooves 12

and 13 by keys or pins 14 and 15, and are passed around the pins, and are spread thereby, and are prevented being withdrawn from the 55 contracted or narrow mouth of the curved grooves 12 and 13, which are approximately cylindrical.

In removing the strap from the cylindrical bar or roll 5 to expose the hone-faces the lever 60 9 is raised or separated from the handle portion 2, as illustrated in Fig. 1 of the accompanying drawings, and when the strap is inside it is tightened by bringing the lever 9 against and in contact with the handle portion 2, as illustrated in Fig. 2 of the accompanying drawings, and the lever 9 is shaped to form a section of the handle of the razor-strop. The lever 9 is provided at its inner end with an ear 16, which forms a continuation of a rib 17 on the inner face of the lever, and is provided with a perforation 18, and is arranged in a recess 19 in the inner face of the handle portion 2 of the body, and is pivotally connected to the latter by a pin 20 75 passing through the body and the perforation 18 of the lever.

It will be seen that the razor-strop is simple and inexpensive in construction, and is adapted to readily expose its hone-faces or 80 its strap and canvas, and that the latter can be readily removed from the strop and its tension adjusted by means of the keys or pins, which are readily removable and can be quickly replaced to take up or let out the 85 strap.

What I claim is—

1. A razor-strop comprising the body provided with a groove having a contracted mouth or opening, the lever hinged to the 90 body and provided with a similar groove, and the strap having its ends arranged in said groove and secured therein by pins or keys, the latter and the strap ends together filling the groove and being larger than the contracted mouth, substantially as described.

2. A razor-strop comprising the body provided with the handle portion 2, the lever hinged to the body at the inner end of the portion 2 and forming a section of the handle 100 of the strop, the cylindrical bar 5, arranged transversely at one end of the body and being of greater thickness than the body and extending on opposite sides of the same, and

the strap passing over the transverse bar and having its ends connected to the body and the lever, substantially as described. 3. A razor-strop comprising the body having one end formed into a handle portion and provided between the handle portion and its other end with hone-faces, the lever conforming to the configuration of the handle portion and provided with a perforated ear hinged to the body, the cylindrical bar 5, arranged at one end of the body and provided with a

recess to receive the same, and the strap having its end secured to the lever and the body, substantially as described.

In testimony that I claim the foregoing as my own I have hereto affixed my signature in presence of two witnesses.

MICHAEL E. REILLY.

Witnesses: J. H. SIGGERS, R. W. DAYTON.
